UNITED STATES PATENT OFFICE.

JOHN O. CARREY, OF ST. LOUIS, MISSOURI, ASSIGNOR TO CARREY ROTARY ENGINE COMPANY, OF ST. LOUIS, MISSOURI, A CORPORATION OF MISSOURI.

BURNER.

1,349,319.

Specification of Letters Patent. Patented Aug. 10, 1920.

Application filed April 26, 1919. Serial No. 292,934.

To all whom it may concern:

Be it known that I, JOHN O. CARREY, a citizen of the United States, residing at the city of St. Louis and State of Missouri, have invented a new and useful Burner, of which the following is a specification.

This invention relates to improvements in burners and consists in the novel construction hereinafter disclosed.

10 An object of the invention is to provide an improved burner whereby continuous combustion may be maintained for the operation of engines and other purposes.

Another object of the invention is to provide a burner including an air passage, a fuel passage, a mixing chamber, and a burner nozzle whereby combustion may be maintained for the purpose of supplying pressure for the operation of engines and 20 other purposes.

With the foregoing and additional advantages in construction in view, I have designed the burner hereinafter described, reference being made to the accompanying 25 drawings, in which:—

Figure 1 is a side elevation of a burner and combustion chamber in which continuous combustion may be maintained.

Fig. 2 is a vertical sectional view thereof, 30 Fig. 3 is a cross sectional view on the line 3—3 of Fig. 2.

As shown in the drawings, the device is mounted in connection with a combustion chamber A and from the following description it will be understood that the invention 35 is adapted for use or practice in the operation of either rotary or reciprocating or heat engines, or in combustion chambers, furnaces, or for other purposes.

40 As shown, the chamber 1 is secured to the engine casing and supports a clamp device 2 by which the burner nozzle 3, preferably of non-metallic refractory material, is supported. As shown, the burner nozzle 45 is formed with a circumferential flange 4 clamped between the clamp 2 and the end of the chamber 1.

Air is admitted into the chamber 1 through 50 a passage 5 terminating in a nozzle 6 within the burner nozzle 3. The fuel is admitted into the chamber 1 through a passage 7 which opens above the upper end of the burner nozzle and above the lower end of the nozzle 6. Thus, the fuel is drawn 55 from the passage 7 into the burner nozzle

3 by the rush of air forced through the passage 5 and the nozzle 6, creating a suction for the fuel.

The construction and arrangement of the parts shown may be varied without departure from the invention and I do not restrict myself to the specific device shown and described.

What I claim and desire to secure by Letters Patent, is:—

1. The combination with a chamber having an exteriorly recessed opening through the wall thereof, of a tubular burner nozzle extending through the opening and projecting on both sides of the chamber wall, 70 a flange on said nozzle, a clamp device seated in the recess and engaging said flange for supporting said nozzle, a casing connected with the wall of the chamber and inclosing the upper end of said burner nozzle, an air 75 passage entering said casing and overlapping the inclosed end of the burner nozzle, and a fuel supply passage entering said casing and arranged so that the suction of the air escaping from said air passage will 80 withdraw fuel from said fuel passage and force the mixture into said chamber.

2. The combination of a casing having an opening therein, a tubular burner nozzle having flared ends mounted in said opening and extending on both sides of the wall of the casing, means for removably supporting the burner nozzle in said opening, a tubular air passage of a less diameter than the burner nozzle extending into the 90 outer end of said burner nozzle, a casing forming a chamber supported by said first named casing and inclosing the air passage and the end of the burner nozzle, and a fuel supply pipe entering said chamber 95 above the upper end of the burner nozzle.

3. The combination of an air pipe having a restricted nozzle at its end, a tubular burner nozzle supported in axial alinement with said air pipe, and slightly overlapping its end, said burner nozzle having a flared opening, a globular casing surrounding the matching ends of said air pipe and said burner nozzle, and a fuel supply passage entering said globular casing at an angle to the air pipe and the burner nozzle and at a point above the open end of the burner nozzle and above the lower end of the air pipe.

4. The combination with a chamber hav-

- ing an opening therein, of a tubular burner nozzle supported in said opening, said nozzle being provided with an external flange, a casing attached to said chamber and inclosing the upper end of said burner nozzle, a clamping member bearing against the flange on said burner nozzle for supporting the same in position, an air passage entering said casing and overlapping the inclosed end of the burner nozzle, and a fuel supply passage entering said casing at a point so that the suction of the air escaping from said air passage will withdraw fuel from said fuel passage.
- 15 5. The combination with a chamber having an opening therein and a recess embracing the outer end of said opening, of a tubular burner nozzle of refractory mate-

rial, having an external flange, said nozzle extending through said opening and projecting beyond the inner and outer surface of the wall of the chamber, a casing inclosing the upper end of said burner nozzle, said casing having a threaded portion extending into said recess, a clamping member adapted to be threaded over said extending end of said casing and to clamp the flange of the nozzle, whereby the nozzle is supported in position in said opening; an air passage entering said casing and overlapping the inclosed end of the burner nozzle, and a fuel supply passage extending into said casing at an angle in respect of the air passage.

JOHN O. CARREY.
